UNITED STATES PATENT OFFICE.

DANIEL SHEETS, OF UNION, OHIO.

GATE.

SPECIFICATION forming part of Letters Patent No. 233,642, dated October 26, 1880.

Application filed March 8, 1880. (Model.)

To all whom it may concern:

Be it known that I, DANIEL SHEETS, of Union, in the county of Montgomery and State of Ohio, have invented new and useful Improvements in Gates, of which the following is a specification.

My invention relates to a form of gate operated automatically by the passing of a vehicle, and is adapted to be operated by hand; and it consists of a double series of parallel bars jointed at the points of intersection, so that the gate is extended or retracted at pleasure, and this motion effects the opening and closing of the same. Devices consisting of trip-irons and levers are used to operate the same automatically.

The accompanying drawings are made a part of this specification, and like letters of reference marked thereon of the different figures 20 designate like parts.

Figure 1 is a side elevation of the gate. Fig. 2 is a top view of the base and a section of the post centrally through the guides. Fig. 3 is an oblique view of the gate and its attachments.

A is a board forming the base, which corresponds to the earth and serves as a support to the superincumbent parts. To the base are secured the posts C and D in vertical position. The post C has mortises to receive the 25 ends of the gate when closed, as shown by dotted lines. The center of the post D is cut out almost the entire length above the base, as indicated by dotted lines. On the back of this post, and near the top, are guides N on both 30 sides of the mortise, to support the friction-rollers O, which are attached to the bar R by means of a pin that forms the axes of the rollers. The curved oscillating rod E is supported 35 on standards at both ends, and at its center is supported on the pin M, which passes through the post and forms the pivotal support of the 40

gate-bar L. The bent projection of the oscillating rod is connected to the gate-bar by a link or equivalent device, as illustrated at Fig. 1. Near both ends are attached arms to the 45 oscillating rod, which are connected to the crank end of the trip-irons by the stirrup or plates U. The trip-irons G have a double bend, the two parts having the relation of right angles, and are secured to the base at a 50 suitable distance parallel to the gate. The trip-irons are identical with those in use in the operation of automatic gates, and are operated by the passing vehicle.

The operation may be thus described: The 55 wheel is driven against that part of the trip-iron that depresses the rear part of the oscillating rod. This carries the gate-bar to a nearly-vertical position, the effect being to close the parts of the gate upon itself within 60 the post, and thus the way is fully open. When the vehicle has passed the gate the part of the trip-iron is struck which elevates the rear extension of the oscillating rod, and thereby the 65 gate is closed.

The construction of the gate is not novel, and consists of a double series of bars crossing each other, and so jointed as to admit of extension and retraction. The hand may be likewise used on the bar R to effect the opening and closing of the gate.

What I claim as my invention, and desire to secure by Letters Patent, is—

The gate B, having arms R and L, in combination with the guide N, post D, oscillating 75 rod E, and trip-irons G, substantially as and for the purposes set forth.

DANIEL SHEETS.
